United States Patent Office.

C. D. WALKES, OF ELYRIA, OHIO.

Letters Patent No. 97,997, dated December 14, 1869.

IMPROVED BED-BOTTOM.

The Schedule referred to in these Letters Patent and making part of the same

To all whom it may concern:

Be it known that I, C. D. WALKES, of Elyria, in the county of Lorain, and State of Ohio, have invented certain new and useful Improvements in Bed-Bottoms; and I do hereby declare that the following is a full and complete description of the same, reference being had to the accompanying drawings, making a part of this specification, in which—

Figure 1 is a top view of the bed-bottom.

Figure 2, a view of the side.

Figure 3, a detached section.

Like letters of reference refer to like parts in the several views shown.

The nature of this invention relates to a bed-bottom, so constructed that a section of the head can be elevated, whereby a person lying upon the bed can be raised to a recumbent posture.

In fig. 1, A represents the frame of the bedstead.

Along the inside of each side rail is a cleat, B, on which rest the ends of the lower range of slats C, fig. 3.

On each of the lower slats rests a spring, D, which is connected to the same at the point x.

E are slats, the extreme ends of which are placed upon the extreme ends of the springs, and thereto secured.

The relative positions of the slats and springs to each other are shown in fig. 3.

This arrangement of slats and springs, and which

constitutes the bed-bottom, is divided in two sections, F G, section F being attached to section G by means of the hinges H, whereby said section F can be elevated to the position shown in fig. 2, by means of the cams I, said cams being secured, one at each end of the shaft J, extending across the head of the bed, to the extreme ends of which are keyed a ratchet-wheel, K, and crank K'.

The practical operation of this adjustable bed-bottom is as follows:

The hinged section is elevated by means of the cams, which, as they are turned, push up the section, against the under side of which it is made to engage, and thereby elevate it more or less, as may be required, and which is retained at any degree of elevation by the pawl and wheel K K'.

This way of elevating the head of the bed-bottom is simple and easily performed. It is also neat, and by no means expensive.

What I claim as my invention, and desire to secure by Letters Patent, is—

A bedstead constructed with cams I, ratchet-wheel and pawl K K', springs D, and slats E C, arranged in the manner as described and for the purpose specified.

C. D. WALKES.
